UNITED STATES PATENT OFFICE.

PAUL HOFFMAN, OF CHICAGO, ILLINOIS, ASSIGNOR TO THE AJAX FORGE COMPANY, OF CHICAGO, ILLINOIS, A CORPORATION OF ILLINOIS.

ARTICULATED RAILWAY CROSSING.

Application filed April 9, 1920. Serial No. 372,456.

To all whom it may concern:

Be it known that I, PAUL HOFFMAN, a citizen of the United States, residing at Chicago, in the county of Cook and State 5 of Illinois, have invented certain new and useful Improvements in Articulated Railway Crossings, of which the following is a specification.

This invention relates to railway crossings and its purpose is to provide an improved articulated or broken joint crossing. The principal object is to provide an improved location and arrangement of the joints so that certain parts of the crossing 10 may be standardized and used in railway crossings of various angles. A further feature of the invention is the provision of a crossing comprising four similar corner pieces or intersections connected by 15 four intermediate rail sections which are similar in size and construction so that they can be interchanged with each other or used with other corner sections where the railway lines cross at different angles. A further object is to provide an improved railway crossing comprising complementary sections which have an improved interlocking connection with each other. Other objects relate to various features of construction and arrangement which will appear 20 more fully hereinafter.

The nature of the invention will be understood from the following specification taken with the accompanying drawings in 25 which one embodiment is illustrated.

In the drawings—

Fig. 1 shows a top plan view of the railway crossing;

Fig. 2 shows a top plan view of one of 40 the joints, the connected parts being separated to illustrate more clearly the interlocking construction;

Fig. 3 shows a transverse sectional view on the line 3—3 of Fig. 2, looking in the 45 direction of the arrows;

Fig. 4 shows a longitudinal sectional view on the line 4—4 of Fig. 2, looking in the direction of the arrows;

Fig. 5 shows a perspective view of the end 50 of one rail section, illustrating the construction of the locking tongues and grooves formed thereon; and

Fig. 6 shows a perspective view of one end of another rail section, illustrating the 55 construction of the tongues and grooves

adapted to cooperate with the tongues and grooves formed on the end of the member illustrated in Fig. 5.

This improved crossing comprises four corner rail sections 10 which may be called 60 the intersections, and these corner sections are connected by four intermediate connecting rail sections 11 which are identical in length and construction. Each corner section 10 comprises two intersecting 65 grooves 12, located at right angles to each other in the embodiment illustrated, and these grooves are adapted to receive the flanges of the car wheels. The tread portions of the car wheels rest upon the traffic 70 rail portions 13 which are formed as integral parts of the corner sections 10 and are located on the outer sides of the grooves 12. On the outer sides of the crossing, each corner section is provided with a guard rail 75 portion 14 located on the opposite side of one of the grooves 12 from the adjacent traffic rail portion 13. These guard rail portions 14 are flared outwardly at their ends, as shown at 14^a and are provided with 80 inwardly projecting webs or foot guards 14^b which extend transversely therefrom and are adapted to engage the webs of the usual traffic rails 15. These traffic rails engage recesses 16 which are formed in the traffic 85 portions 13 of the corner sections so that the heads of the rails 15 form continuations of the traffic portions 13 and the inner sides of the rail heads lie in the same vertical 90 planes with the walls of the grooves. Other angular guard rail portions 17 are formed as continuations of the guard rail portions 14 on the inner side of the intersection of each pair of grooves 12.

The intermediate rail sections 11, by 95 which the corner sections are connected, comprise traffic portions 19 adapted to aline with the traffic portions 13 of the corner sections, and these connecting rail sections are further provided with guard rail portions 20 which aline with the guard rail portions 14 and 17. Grooves 21 are formed in the upper surfaces of the connecting rail sections 11 between the traffic portions 19 and the guard rail portions 20, and these 100 grooves 21 aline with the grooves 12 in the corner sections. These rail sections 10 and 11 are connected together by means of angular fish plates or knee braces 25 and 26, the former being located on the outer 105 110

sides of the corner sections, and the members 26 being located on the inner sides thereof. These fish plates fit into the spaces between the heads of the rail sections 10 and 11 and overlap the joints between the rail sections 10 and 11 and also between the rail section 10 and the rail 15. The webs of the connected rail sections are provided with transverse apertures 27 which are adapted to be engaged by joints 28 for securing these parts in assembled relation.

In addition to the knee braces and bolts which are applied for securing the rail sections together, the abutting ends of the corner sections 10 and the intermediate sections 11 are provided with interfitting tongue and groove connections which permit some relative play or movement of these sections as the rolling stock passes over the crossing but they prevent any considerable relative displacement of the sections 10 and 11 either horizontally or vertically. This interlocking connection is illustrated particularly in Figs. 2 to 6, inclusive. Each inner end face of each corner section 10 is provided with a vertical groove 30 of semicircular cross section adapted to be engaged by corresponding semicircular lugs 31 which are formed integrally with the end face of the adjacent connecting section 11. Each section 11 is provided between the lugs 31 with a horizontal extending groove 32 of semicircular cross section which is adapted to be engaged by the semicircular lugs 33 which are formed on opposite sides of the groove 30 as integral parts of the corner sections 10. When the wheels pass over the crossing, the parts 30-31 permit some lateral swaying of the sections 10 and 11 and the interlocking parts 32-33 permit some relatively vertical movement thereof so that the corner sections 10, upon which the pounding action of the wheels takes place as the tread surface of the wheels passes across the grooves 12, are permitted to yield somewhat with respect to the intermediate sections 11, thus preventing the breakage which would be liable to occur if the entire crossing were formed in one piece. An important advantage of this construction is that all of the intermediate connecting sections 11 are similar in length and design so that they may be interchanged with any shape or size of the connected corner sections, which feature permits the use of the intermediate rail sections as standard parts with the railway crossings of various angles. The corner sections 10 for a particular angle of crossing are also identical in construction at diagonally opposite corners of the crossing. Each arm of each corner section 10 which extends outwardly from the intersection is similar to the other corresponding arm and each of the short arms which extends inwardly and

connects with one of the sections 11 is similar in length and size to the other corresponding arm. Thus any corner section 10 may be interchanged with any diagonal section 10 in the same crossing or any other 70 crossing of the same angle. Where the intersecting railway lines cross at right angles, all of the corner sections 10 are alike.

Although I have shown and described a 75 certain form of the invention for purposes of illustration, it will be understood that it may be constructed in various other forms without departing from the scope of the appended claims.

I claim:

1. A railway crossing comprising complete corner sections, and complete intermediate rail sections located between each pair of corner sections and connected thereto. 85

2. A railway crossing comprising corner sections having traffic rail and guard rail portions, intermediate rail sections having integral traffic rail and guard rail portions located between each pair of corner sections, 90 and means connecting said intermediate members with said corner sections to permit limited relative movement thereof.

3. A railway crossing comprising corner sections, and intermediate rail sections terminating inwardly from the angles of said corner sections and connected to said corner sections. 95

4. A railway crossing comprising corner sections having inwardly directed arms, and 100 intermediate rail sections terminating in planes normal to their longitudinal axes and connected to the ends of oppositely disposed arms.

5. A railway crossing comprising corner 105 sections having arms of equal length directed inwardly, and intermediate sections located between opposite arms, said arms having interlocking connections to permit relative movement thereof.

6. A railway crossing comprising corner sections having arms of equal length directed inwardly, and intermediate sections located between opposite arms, said arms and said intermediate sections having interlocking 115 tongue and groove connections adapted to prevent relative movement thereof horizontally or vertically beyond predetermined limits.

7. A railway crossing comprising corner 120 sections, each having a pair of inwardly directed arms, intermediate sections of equal length located between oppositely disposed arms, and tongue and groove connections extending vertically and horizontally on the 125 contacting faces of said intermediate sections and said corner sections.

8. A railway crossing comprising corner sections, and intermediate rail sections located between each pair of corner sections 130

and connected thereto, said intermediate rail sections being similar and interchangeable with other intermediate rail sections in crossings of different angles.

- 5 9. A railway crossing comprising corner sections each having four complete radiating arms, the inwardly directed arms terminating in planes normal to their longitudinal axes, and a plurality of intermediate rail
10 sections each located between two of said corner sections and contacting on their end faces with the ends of inwardly directed arms.

10. A railway crossing comprising corner sections having inwardly extending arms of 15 equal length, and intermediate rail sections of equal length located between each pair of corner sections and each connected to oppositely disposed inwardly extending arms, said intermediate rail sections being similar 20 and interchangeable with other intermediate rail sections in crossings of different angles.

In testimony whereof, I have subscribed my name.

PAUL HOFFMAN.
